TABULATING MACHINE

Frederick C. Blomfield, Coldwater, and Magnus H. Johanson, Rochester, N. Y.; said Johanson assignor to said Blomfield

Application May 24, 1938, Serial No. 209,800

13 Claims. (Cl. 281—1)

The present invention relates to a tabulating machine and more particularly to one for successively presenting to view different portions of separate sheets to facilitate the application of data thereto or consideration of previously entered items thereon.

One object of the invention is to provide an improved machine of the class described which embodies a simplified construction and which 10 is convenient to operate, efficient in service, and comparatively inexpensive to manufacture.

Another object of the invention is to provide in a machine of this class a novel construction embodying stationary supporting means adapted to receive a plurality of sheets or forms, together with means for simultaneously advancing the sheets thereon and for successively presenting to view different predetermined or corresponding portions of the sheets in juxtaposition 15 to permit the operator to readily compare or summarize data applied thereto.

A further object of the invention is to provide an improved machine of the class described having sheet supporting surfaces each adapted to receive one of a plurality of sheets to be moved relative to said surfaces to successively position different predetermined portions of the sheets thereon, and the surfaces being of a character 20 to permit data to be readily written on said portions when in overlying engagement with said surfaces.

A further object of the invention is to provide in a machine of the class described, improved means for simultaneously feeding a plurality of 25 sheets, step by step, to present to view predetermined portions thereof containing items of account or other data, in juxtaposition one relative to another and substantially in a plane.

To these and other ends the invention resides 30 in certain improvements and combinations of parts, all as will be hereinafter more fully described, the novel features being pointed out in the claims at the end of the specification.

In the drawings:

45 Fig. 1 is a front elevation of a machine embodying the invention;

Fig. 2 is a top plan view of the same;

Fig. 3 is a view similar to Fig. 2 with the cover of the machine swung to vertical position and 50 with the sheet supporting table removed;

Fig. 4 is a part sectional elevation with the carriage for moving the sheets shown at its uppermost position;

Fig. 5 is a sectional elevation on the line 5—5 55 of Fig. 3 drawn to an enlarged scale and illus-

trating a brake for the driving shaft of the mechanism for raising and lowering the carriage for effecting a step by step movement of the data bearing sheets;

Fig. 6 is a plan view of one end of the sheet supporting table; 5

Fig. 7 is a fragmentary sectional elevation on line 7—7 of Fig. 2 with the sheet positioning carriage in elevated position;

Fig. 8 is a somewhat similar view with the carriage shown in partially lowered position; 10

Fig. 9 is a transverse sectional elevation through one of the sheet engaging and advancing members of the carriage drawn to an enlarged scale and showing a spring for gripping 15 the sheet moved to release position by a cam rod;

Fig. 10 is a detailed view of the cam rod shown in section in Fig. 9, and

Fig. 11 is a view illustrating by way of example a portion of one of a number of different sheets or forms to be used in connection with the present machine. 20

The same reference numerals throughout the several views indicate the same parts. 25

The present invention relates to a machine on which to assemble a plurality of sheets with corresponding portions thereof in juxtaposition, the machine including means for simultaneously advancing the sheets to successively position and present said portions to view for a purpose described hereinafter. The sheet or form shown by way of example in Fig. 11 constitutes merely one of a number of different sheets or forms adapted to be handled by the present machine. 30 The sheet illustrated preferably includes a plurality of columns or data receiving portions designated generally by the reference numerals 1 to 6, inclusive, and upon which may be entered data of any desired nature, under appropriate 35 headings and which may relate, for example, to expense accounts, sales records, cost sheets, pay checks or vouchers, accounts receivable and other financial or statistical data. On the sheet illustrated, certain of the columns each contains different account numbers with spacings for different individual amounts and with corresponding item numbers opposite said spacings, while other columns may include headings for debit and credit accounts or for any other entries desired. 40 45 50

It will be understood that the present machine is designed to accommodate a number of such sheets, having a supporting surface corresponding to each, the surfaces preferably being stationary and disposed one adjacent another and 55

corresponding in width substantially to the width of the columns of the sheets, in order that the corresponding columns of the different sheets may be displayed one adjacent another to facilitate summarizing or comparison of the data thereon, or the transposing of the same to journals or ledgers, as desired.

Moreover, the individual sheet supporting surfaces of the machine are of such a nature as to permit data to be written in the columns of the different sheets while overlying said surfaces, when it is desired to use the machine for this purpose, in addition to that of advancing the sheets simultaneously and step by step to position the corresponding columns of the different sheets in juxtaposition one relative to another.

Referring to the drawings, 10 designates generally a substantially rectangular casing for the sheet feeding mechanism, the casing being preferably supported by suitable legs 11, as shown in Fig. 1. The casing is provided at its upper end with suitable supporting means 12 upon which to position the data bearing sheets, one of which is indicated at 13, the supporting means being preferably in the form of a table having flanged edge portions 14 extending downwardly on the side walls of the casing, as shown in Fig. 4. The table is provided with a series of slots 15 having therebetween substantially flat stationary supporting surfaces or members 16 for the sheets, of a width corresponding substantially to that of the columns of the sheets.

Within the casing 10 beneath the table 12 is provided suitable means for simultaneously feeding the sheets 13 step by step on the stationary supporting members 16, said means preferably being in the form of a carriage designated generally by the reference numeral 17. The carriage is of rectangular construction and is guided in its up and down movements within the casing by the front and rear vertically extending guide members 18 and 19, respectively, which are suitably secured on the inner faces of the walls of the casing 10, Fig. 3.

45 The carriage includes a series of transversely extending members 20 which are spaced apart distances substantially equal to the distances between the slots 15 of the table 12 and which are preferably aligned with the slots, as shown in Fig. 7, said members having their ends suitably connected with the front and rear walls of the carriage.

55 Each of the members 20 is provided with a series of spaced lugs 21 for receiving the leading edge 13a of one of the data bearing sheets 13 whereby each sheet may be properly positioned within the machine in advance of the feeding operations. Suitable means, such, for example, as the springs 22 are provided for cooperation with the transverse members 20 of the carriage to retain the sheets thereon and to insure movement of the same over the surfaces of the supporting members 16 during movement of the carriage downwardly from the position shown in Fig. 7, the springs being suitably connected at their lower ends with the members 20.

70 After completing the sheet advancing or feeding operations by moving the carriage to its lowermost position, the springs 22, corresponding to each of the transverse members 20, can be moved to the position shown in Fig. 9 to free the sheets for withdrawal from the machine.

75 Means for moving the springs to release the sheets comprises, in each case, a rod 23 having a cam surface 23a, the rear end of the rod being

journalled in a metal strip 24 suitably secured on the rear wall of the carriage, while the other end of the rod is extended through the front wall of the carriage and a metal strip 25 thereon, as well as through a slot 26 in the front wall of the casing 10, Figs. 1 and 3. The outer end of the rod is provided with an operating handle 27 by which the rod may be rotated to cause the cam face 23a to engage and move the springs to release the sheet whereby to free it for withdrawal from the machine.

Any suitable means may be provided for moving the carriage such, for example, as the racks 28 and 29 on the end walls thereof, the shafts 28a and 29a having pinions 28b and 29b meshing, respectively, with the racks 28 and 29, the shaft 30 having a gear 31 meshing with and driven by a gear 32 on the driving shaft 28a and also having a gear 33 meshing with a similar gear 34 on the shaft 29a and by which the latter is driven. The shafts 28a, 29a, and 30 are supported each by a plurality of bearings 34 suitably connected to the walls of the casing, Fig. 3.

The driving shaft 28a is extended through the front wall of the casing into a housing 35 detachably secured on said wall and provided with a removable cover 36. A crank 37 is provided on the outer end of the drive shaft 28a for operating the same. Fixed on the shaft 28a within the housing 35 is a flanged brake wheel 38, associated with which is a yoke 39 having a semi-circular brake member 40 yieldingly held in engagement with the brake wheel by means of the springs 41 on bolts 42 which are extended through the ends of the yoke and the springs into the walls of the housing 35, Fig. 5.

By turning the crank 37 to operate the shaft 28a and the shafts 30 and 29a connected therewith the carriage 17 may be moved downwardly on the guides 18 and 19 from the elevated position shown in Fig. 7 to the lowered position shown in Fig. 8 whereby to simultaneously advance the sheets 13 each a distance equal to the width of one of the six columns of the sheet, designated by the reference numerals 1 to 6, inclusive, in Fig. 11. It will be understood that the carriage may be lowered by a step by step movement whereby to successively position the portions of the sheets corresponding to said columns on the supporting members 16. It will also be understood that upon completion of each of said operations that the brake member 40 through frictional engagement with the wheel 38, will retain the carriage at the different positions to which it is moved.

It will be apparent that upon completion of the sheet advancing operations that the sheets may be released by moving the handles 27 of the cam rods 23 each to a dotted line position corresponding to that indicated in the upper left hand corner of Fig. 1 whereby to move the springs 22 to free the sheets. Upon release of the sheets in this manner they can, by gripping the portions 13b of the sheets with the fingers be readily withdrawn from the machine.

The casing 10 is provided with a top 43 hinged at 44 and adapted to be swung from the normal horizontal service position shown in Fig. 2 to the substantially vertical position shown in Fig. 3, at which it will be arrested by suitable stops 45a on the rear wall of the casing. The top 43 has an opening of a size slightly larger than the portion of the table 12 on which the data bearing sheets 13 are disposed in order that the sheets

may readily be observed when the top is in lowered position.

The top is provided at the left side thereof, as viewed in Figs. 1 and 2, with downwardly and inwardly turned portions 45 and 46 for receiving the head 47 of a T-square or similar member 48 for movement over the data bearing sheets to facilitate reading of the characters of the horizontal lines of the sheets. The free end of the 10 T-square is provided with a downwardly turned portion 49 which engages the downwardly turned portion 45b and the top and which serves to both guide the T-square and to prevent longitudinal movement of the same in one direction.

15 The top is provided with a plurality of wires or rods 50 having their ends extended downwardly through openings in the ends of the top and suitably secured therein. The wires serve to maintain the sheets in proper relation upon the 20 upper faces of the supporting members 16 without interfering with the proper advancement of the sheets. The portion of the T-square overlying the data bearing sheets is slightly offset in an upward direction, as shown in Fig. 3, to permit it to pass freely over the wires 50 when adjusting the T-square between its limits of movement on the top.

The data bearing sheets 13 can readily be positioned upon the supporting members 16 merely by inserting each sheet downwardly through one of the slots 15 and then moving the portion 13a of the sheet downwardly through the next succeeding slot, between the member 20 and the springs 22 thereon until the leading edge 13a of the sheet engages the stops 21 as shown in Fig. 7. By thus positioning the sheets within the machine the column 6 of each will overlie one of the supporting members 16 as shown in Fig. 2. With the sheets thus assembled in position 40 upon their respective supporting members data may be applied to the sheets by writing or marking it thereon in any or all of the columns as desired, provided the sheets have not previously been supplied with the desired data. Then by 45 turning the crank 37 the sheets will be simultaneously advanced to position column 5 of each in overlying relation with respect to one of the supporting members 16, after which the necessary data can be entered by writing it in said columns, it being understood that the surfaces of 50 the stationary supporting members 16 are preferably made flat and smooth, whereby to afford a suitable background for the sheets which will permit the characters to be readily applied freely in a satisfactory manner.

While the construction of the sheet supporting means is such as to permit data to be supplied to the sheets when in overlying relation relative to said supporting members, it will be understood that all items or data of any kind to be applied 60 to the sheets may be entered thereon before positioning the sheets within the machine, in case it is desired to make use of the machine only as a means for successively displaying the corresponding 65 columns of the sheets in juxtaposition in order to more readily observe, check, or summarize the data thereon.

The machine shown and described herein is particularly advantageous in that it serves to 70 greatly reduce the time heretofore consumed in the manual handling of a considerable number of record bearing sheets, preparatory to and during consideration or tabulation of the data thereon. It also affords convenience in the presentation 75 of the sheets for consideration by the opera-

tor as well as tends to insure accuracy in the calculations or observations to be made, and facilitates the application of data to the sheets in cases where it may be desired to enter various items thereon after the sheets have been positioned within the machine.

While one embodiment of the invention has been disclosed, it is to be understood that the inventive idea may be carried out in a number of ways. This application is therefore not to be limited to the precise details described, but is intended to cover all variations and modifications thereof falling within the spirit of the invention or the scope of the appended claims.

15 We claim:

1. In a machine of the class described, means forming a series of spaced adjacently disposed stationary surfaces for supporting data bearing sheets, and means movable vertically in the machine for engaging and simultaneously moving the sheets, said means being operable to effect a step by step movement thereof to successively position different predetermined portions of the sheets in juxtaposition one relative to another on said surfaces.

2. A frame having a plurality of spaced adjacently disposed supporting members each for a data bearing sheet adapted to have one end portion positioned on one of the members with the opposite end portion depending from said member, means having parts for engaging the first mentioned end portions of the sheets, and means for moving said parts in a rectilinear manner to simultaneously move the sheets, said means being operable to effect a step by step movement thereof to successively position different predetermined portions of each sheet on the supporting member corresponding thereto so as to present said different predetermined portions of the sheets to view in juxtaposition one relative to another.

3. In a machine of the class described, means forming a series of spaced adjacently disposed surfaces for supporting data bearing sheets, a carriage mounted adjacent said surfaces, means on the carriage for engaging and simultaneously moving the sheets upon movement of the carriage, and means for effecting a step by step movement of the carriage in a rectilinear manner to successively position different predetermined portions of the sheets in juxtaposition one relative to another on said surfaces.

4. In a machine of the class described, a table having a series of slots with substantially flat surfaces therebetween each adapted to support a sheet with opposite portions of the sheet depending therefrom through two of the slots, and means movable in a rectilinear manner for engaging and simultaneously moving the sheets, said means being operable to effect a step by step movement thereof to successively position different predetermined portions of the sheets in juxtaposition one relative to another on said surfaces.

5. A table having a plurality of stationary supporting members each for a sheet adapted to be disposed thereon with opposite portions of the sheet depending therefrom, a device movable in a rectilinear manner for moving each sheet comprising relatively movable parts for engaging the sheet, means for simultaneously moving said devices to move the sheets on the supporting members, means for effecting a step by step movement of said means to successively position different predetermined portions of the sheets in juxtaposition one relative to another on the sup-

porting members, and means for effecting release of one of the parts of each of said devices to release the sheet held thereby.

6. A frame having a plurality of spaced supporting members each for a sheet adapted to be disposed thereon with opposite portions of the sheets depending therefrom, relatively movable cooperating parts for receiving one of the depending portions of each of the sheets, means for operating said parts in a rectilinear manner to simultaneously advance the sheets on said members, said means being operable to effect a step by step movement of said parts to successively position different predetermined portions of each sheet on the supporting member corresponding thereto so as to present said different predetermined portions of the sheets to view in juxtaposition one relative to another, and separate independent members for effecting relative movement between the cooperating receiving parts for each sheet to release the sheet.

7. A frame having a plurality of spaced adjacently disposed supporting members each for a sheet adapted to have one end portion placed thereon with the opposite end portion depending therefrom, a carriage movable beneath the frame, parts on the carriage for engaging the first mentioned end portion of each of the sheets, and means for operating the carriage to simultaneously move said parts to move the sheets on said supporting members, said means being operable to effect a step by step movement of the carriage to successively advance the sheets to position different predetermined portions of each on the supporting member corresponding thereto so as to present said different predetermined portions of the sheets to view in juxtaposition one relative to another.

8. A table comprising a plurality of spaced supporting members each for a sheet adapted to be positioned thereon with opposite portions of the sheet depending therefrom, a carriage movable beneath the table and having a part corresponding to each of the supporting members, said parts each being adapted to receive one depending portion of each sheet, resilient means for cooperation with each of said parts to hold the last mentioned portion of the sheet thereon, and means for effecting a step by step movement of the carriage to move the sheets on said supporting members and to successively present different predetermined portions thereof to view in juxtaposition one relative to another.

9. A table comprising a plurality of spaced supporting members each for a sheet adapted to be positioned thereon with opposite portions of the sheet depending therefrom, a carriage movable beneath the table and having a part corresponding to each of said supporting members, said parts each being adapted to receive one depending portion of each sheet, one or more springs associated with each of said parts for engaging the portion of the sheet disposed thereon, means for effecting a step by step movement of the carriage to move the sheets on said supporting members and to successively present different predetermined portions of the sheets to view in juxtaposition one relative to another, and means corresponding to each of said parts

for moving the springs associated therewith to release the sheet advanced thereby for withdrawal from the machine.

10. A table comprising a plurality of spaced supporting members each for a sheet adapted to be positioned thereon with opposite portions of the sheet depending therefrom, a carriage movable beneath the table and having a part corresponding to each of the supporting members, said parts each being adapted to receive one depending portion of each sheet and having abutments for receiving the free edges of said portions to position the sheets in a predetermined relation one relative to another, one or more springs on each of said parts for engaging the portion of the sheet disposed thereon, means for effecting a step by step movement of the carriage to move the sheets on said supporting members to present different predetermined portions thereof to view in juxtaposition one relative to another, and a cam element corresponding to each of said parts for moving the springs thereon to release the depending portion of the sheet held thereby.

11. In a machine of the class described, a frame having a series of spaced substantially parallel sheet supporting members, a carriage movable transversely of said sheet supporting members, individual sheet positioning elements on the carriage each corresponding to one of said sheet supporting members, each of said elements including means for engaging a portion of the sheet disposed on the supporting member corresponding thereto, and means for moving the carriage to simultaneously move said sheet positioning elements to move the sheets on said supporting members.

12. In a machine of the class described, a frame having a series of spaced substantially parallel sheet supporting members, a carriage movable transversely of said sheet supporting members, individual sheet positioning elements on the carriage each corresponding to one of said sheet supporting members, each of said elements including relatively movable parts for engaging a portion of the sheet disposed on the supporting member corresponding thereto, means for operating the carriage to simultaneously move said sheet positioning elements to move the sheets on said supporting members, and a device associated with each of said sheet positioning elements for moving one of the parts thereof to release the sheet held thereby.

13. In a machine of the class described, in combination, a table surface having a plurality of parallel slots therein, said slots being arranged so that a plurality of sheets may be supported on the surfaces between the slots with the ends of the sheets extending through adjacent slots, means located below the table surface for moving the sheets step by step to successively position different corresponding portions of the sheets in juxtaposition one relative to the other, said last mentioned means being movable as a whole from one position to the other with respect to the table surface and maintaining the sheets unrolled between their ends.

FREDERICK C. BLOMFIELD.
MAGNUS H. JOHANSON.
